Fig. 1

Fig. 2

Fig. 3

Fig. 6

Fig. 4

Fig. 5

FIG. 1 is a perspective elevation view of a roller traveller for a sailboat according to my invented design.

FIG. 2 is a top view of the roller traveller shown in FIG. 1.

FIG. 3 is a front elevation view of the roller traveller shown in FIG. 1.

FIG. 4 is a back elevation view of the roller traveller shown in FIG. 1.

FIG. 5 is a bottom view of the roller traveller shown in FIG. 1.

FIG. 6 is an end elevation view of the roller traveller shown in FIG. 1.

I claim:

The ornamental design for a roller traveller for a sailboat, as shown.
